United States Patent Office

Des. 205,966
Patented Oct. 11, 1966

205,966

HAMPER

Robert A. O'Neil, Pittsburgh, Pa., assignor to Fesco, Inc.,
New York, N.Y., a corporation of Delaware

Filed July 8, 1965, Ser. No. 86,088

Term of patent 14 years

(Cl. D58—4)

I claim:

The ornamental design for a hamper, as shown.
